CARLINE ASSEMBLY

Charles David Bonsall, Pittsburgh, Pa., assignor
to P. H. Murphy Company, New Kensington,
Pa., a corporation of Pennsylvania

Application March 7, 1935, Serial No. 9,737

3 Claims. (Cl. 108—5.7)

This invention relates to carline assemblies for car roofs, especially car roofs of the kind having hatchways therein. The principal objects of the present invention are to devise a strong and rigid light-weight carline assembly having hatchway openings framed therein, and to enable the complete carline assembly to be applied to the car as a separate unitary structure. Other objects are simplicity and cheapness of construction and compactness of design. The invention consists in the unit carline assembly and in the constructions, combinations and arrangements of parts hereinafter described and claimed.

In the accompanying drawing, which forms part of this specification and wherein like symbols refer to like parts wherever they occur,

Fig. 1 is a plan view of a carline assembly embodying my invention, showing it secured to the side plates of a railway car,

Fig. 2 is a vertical central longitudinal section of the carline assembly on the line 2—2 in Fig. 1; and

Fig. 3 is a vertical cross-section on the line 3—3 in Fig. 1.

Referring to the accompanying drawing, my carline unit or assembly comprises a pre-assembled framework A adapted to span from side plate B to side plate B of a refrigerator car body and defining one or more hatchway openings C therein. Said frame comprises horizontally spaced side frame or carline members 1 connected by pairs of horizontally spaced cross members 2, said side and cross members defining the hatchway opening C in said frame. As shown in the drawing, the side and cross frame members are metal bars preferably of oblique angle section arranged with their sides converging downwardly around the hatchway openings C so as to conform to the downwardly converging sides of hatchway liners or hoppers of the kind shown in my copending application Serial No. 5,621 filed February 8, 1935. The cross members 2 of the frame have their ends welded or otherwise rigidly secured to the side frame members 1 flush with the tops thereof. Each end of each side frame member 1 has one leg of a metal angle bracket 3 riveted or otherwise secured thereto, whose other leg is adapted to be rigidly secured to the car side plate.

An important advantage of the hereinbefore described carline assembly is that it can be assembled off the car and furnished for application to the car as a complete unitary structure. The side frame members of this preassembled unit function as carline members to strengthen and stiffen the roof frame of the car; and the openings defined by the side and cross-frame members of said unit define the hatchways in the car roof. The downwardly converging sides of the side and cross frame members of the carline assembly are adapted to form supporting seats for the converging sides of the lining or hopper elements of the hatchway construction; and the top flanges of said members form supports for the roof of the car.

What I claim is:

1. A carline assembly adapted for application as a complete unit to a car roof having hatchways therein, said carline assembly comprising spaced carline members connected by spaced cross-members, said members forming openings adapted to define the hatchways in said car roof, said members comprising metal angles, arranged with their top flanges flush and extending outwardly from said hatchway openings.

2. A carline assembly adapted for application as a complete unit to a car roof having hatchways therein, said carline assembly comprising horizontally spaced carline members rigidly connected by horizontally spaced cross-members, said members cooperating to form openings adapted to define the hatchways in said car roof, said members comprising oblique metal angles arranged with their tops flush and their sides converging downwardly around the hatchway openings.

3. A carline assembly adapted for application as a complete unit to a car roof having a hatchway therein, said carline assembly comprising spaced metal carline members, connected by metal members forming an opening in said carline assembly adapted to define a hatchway in said car roof, said members being provided with lateral top flanges arranged flush with each other to form a continuous supporting surface around said opening.

CHARLES DAVID BONSALL.
